UNITED STATES PATENT OFFICE.

CLAUDE B. KISHLER, OF NEW YORK, N. Y.

FOLDABLE EGG-BOILER.

1,093,337.

Specification of Letters Patent. Patented Apr. 14, 1914.

Application filed October 17, 1913. Serial No. 795,693.

To all whom it may concern:

Be it known that I, CLAUDE B. KISHLER, a citizen of the United States, and a resident of New York, county and State of New York, have invented a certain new and useful Improvement in a Foldable Egg-Boiler, of which the following is a full, clear, and exact specification.

This invention relates to a class of devices 10 adapted to be used for culinary purposes.

My invention has for its object primarily to provide a form of boiler designed to be used for permitting eggs to be boiled without the shells thereof being cracked or damaged 15 as well as serving to permit the eggs to be conveniently removed from the water for consumption without risk of injury to the person preparing the eggs, and wherein are employed a number of yielding pockets 20 made of spring wire which are convoluted in parabolic shapes for safely carrying the eggs.

Another object of the invention is to provide means which serves to pivotally connect the pockets to a handle, or support whereby two or more of the pockets may be hingedly swung to folded positions so that the boiler may be placed in a comparatively small container for boiling a few eggs as 30 well as permitting a large number of the devices to be packed into a limited space for transportation.

A further object of the invention is to provide a foldable egg boiler of simple and 35 efficient construction, and which is susceptible of being made in various sizes and shapes.

A practical embodiment of the invention is represented in the accompanying drawing forming a part of this specification in 40 which similar characters of reference indicate corresponding parts in all the views, the said invention being more fully described hereinafter and then pointed out in the appended claims.

45 In the drawing, Figure 1 is a perspective view of one form of foldable egg boiler embodying my invention. Fig. 2, is a top plan view showing in solid lines the manner of folding the boiler and indicating in 50 dotted lines the position of the egg holders when not folded. Fig. 3 is a fragmentary view showing a side elevation of one of the pockets of the boiler and the manner of pivoting the pockets to the handle or support 55 of the device.

The device, or foldable egg boiler has a

handle, or support 10 which is in the form of a vertically disposed rod or post 11 having a ring 12 upon its upper end to permit the boiler to be conveniently carried by a person. Arranged in the formation of a circle around the lower end portion of the post 11 of the handle 10, and spaced suitable distances therefrom, are a number of yielding pockets, as 13, 14, 15, 16, 17, 18, and 60 while I show six of the pockets in the drawing it will be understood that forms of the device may be made wherein a greater or less number of the pockets may be employed. The yielding pockets 13, 14, 15, 16, 17, 18 65 are alike in formation, and each of said pockets is preferably made of spring wire formed into a parabolic shape to conform with the shape of an egg for permitting the egg to be retained therein as shown in dotted 70 lines at 19, without danger of its shell being cracked or damaged.

Extending laterally from the upper part of each of the pockets 13, 14, 15, 16, 17, 18 75 is an integral arm 20, and the free end portion of each of these arms is bent downwardly at a right angle to provide a stem, as 21. All of the stems 21 are arranged around the post 11 of the handle 10, and serving as means for pivotally fastening 80 the stems 21 to the post 11, encircling all of the stems is a sleeve 22 which may be made of spirally bent wire. The sleeve 22 is of sufficient diameter to provide around the lower end of the post 11 an annular recess 85 23 in which the stems are disposed, and this recess is of a width so that the stems will rotate therein. In order to hold the sleeve 22 against displacement upon the handle 10 on the lower end of the post 11 is a head 90 24, and on the post above the head is a collar 25 which supports the lower end of the sleeve. By pivotally connecting the pockets in this manner to the handle 10 the pockets may be swung circumferentially with relation thereto for permitting two or more of the pockets to slide together to a folded 95 position if desired so that the boiler may be used in conjunction with a comparatively small container for boiling a few eggs as 100 well as permitting a large number of the devices to be packed into a limited space for transportation.

In the foregoing description, I have embodied the preferred form of my invention, 110 but I do not wish to be understood as limiting myself thereto, as I am aware that modi-

fications may be made therein without departing from the principle, or sacrificing any of the advantages of this invention, therefore I reserve to myself the right to make such changes as fairly fall within the scope of the appended claims.

Having thus described my invention, I claim as new and desire to secure by Letters Patent:-

- 10 1. A foldable egg boiler of the character described, comprising a handle, a plurality of pockets formed of spring material convoluted in parabolic shapes, said pockets being disposed laterally with relation to the handle, and means provided upon the handle for pivotally connecting the pockets thereto, whereby the pockets may be swung circumferentially of the handle so as to slide together to a folded position.
- 15 2. A foldable egg boiler of the character described, comprising a handle having an annular recess, a plurality of pockets formed of spring material convoluted in parabolic shapes, said pockets being disposed laterally with relation to the handle, and a plurality of stems movably inserted in the annular recess of the handle, whereby the pockets may be swung circumferentially of the handle so as to slide together to a
- 20 3. A foldable egg boiler of the character

described, comprising a handle having a post, a sleeve provided upon the post, a plurality of spirally constructed parabolic shaped pockets disposed laterally with relation to the handle, and means provided upon each of the pockets, and engaging the sleeve, whereby the pockets may be swung circumferentially of the handle so as to slide together to a folded position.

4. A foldable egg boiler of the character described, comprising a handle having a post, a sleeve provided upon the post, said sleeve being of greater diameter than the post to provide an annular recess around the post, a plurality of spirally constructed parabolic shaped yielding pockets disposed laterally with relation to the handle, a plurality of arms, one extending from each of the pockets, and a plurality of stems, one extending at an angle from the arm of each pocket and all of the stems being rotatably disposed in the annular recess around the post, whereby the pockets may be swung circumferentially of the handle so as to slide together to a folded position.

This specification signed and witnessed this sixteenth day of October A. D. 1913.

CLAUDE B. KISHLER.
